UNITED STATES PATENT OFFICE.

HEINRICH SCHULZ, OF WORMS, GERMANY.

DRYING OF PATENT-LEATHER.

1,137,671.

Specification of Letters Patent. Patented Apr. 27, 1916.

No Drawing.

Application filed March 26, 1915. Serial No. 17,302.

To all whom it may concern:

Be it known that I, HEINRICH SCHULZ, a subject of the German Emperor, and resident of 57 Alzeyerstrasse, Worms-on-the-5 Rhine, Germany, have invented certain new and useful Improvements in Drying of Patent-Leather, of which the following is a specification.

The drying of patent leather causes, as is 10 well known, considerable difficulties. In recent times artificial, and in particular mercury light has been substituted instead of sun-light for the final drying. However, it is not always possible to obtain perfectly 15 satisfactory results with the aid of artificial light, and various precautions have to be observed. Among others a powerful ventilation is necessary in order to prevent the formation of ozone and the detrimental effect 20 thereof. Particularly in summer, when higher temperatures prevail, the drying by aid of artificial light will cause much difficulty. It has, now, been found that far better results may be obtained if some ammonia 25 is placed into the chamber in which the leather is exposed to the action of the light, so that the patent leather is exposed to the

action of light and ammonia, simultaneously. Thereby the acid components of the varnish occurring under action of the high 30 oxidization caused by the light are neutralized, whereby a considerably increased adhesive power of the patent leather is obtained.

I claim:

1. The herein-described method of drying patent leather which comprises subjecting the leather to the action of light and ammonia vapors.

2. The herein-described method of drying patent leather which comprises simultaneously subjecting the leather to the action of light and ammonia vapors.

3. The herein-described method of drying patent leather which consists in first drying 45 the leather in an oven and then subjecting the leather to the simultaneous action of light and ammonia vapors.

In witness whereof I have hereunto set my hand in presence of two witnesses.

HEINRICH SCHULZ.

Witnesses:

ROBERT MICHALSKY,
HENRY HASPER.
